FLOYD T. TAYLOR, OF NEW YORK, N. Y., ASSIGNOR TO THE CUTLER-HAMMER MFG. CO., OF MILWAUKEE, WISCONSIN, A CORPORATION OF WISCONSIN.

MOTOR-CONTROLLER.

1,098,134.

Specification of Letters Patent.

Patented May 26, 1914.

Application filed July 28, 1909. Serial No. 510,108.

To all whom it may concern:

Be it known that I, FLOYD T. TAYLOR, a citizen of the United States, residing at New York, in the county of New York and State of New York, have invented new and useful Improvements in Motor-Controllers, of which the following is a full, clear, concise, and exact description, reference being had to the accompanying drawing, forming a part of this specification.

My invention relates to improvements in controllers for electric motors.

Where it is desired to regulate the speed of a motor by means of armature resistance, it sometimes occurs that the motor will not start with the regulating resistance in circuit. This may be due to the size of the motor or to the friction of rest of the mechanism driven thereby. It, therefore, becomes necessary to remove all or a portion of the regulating resistance from circuit to start the motor and then to reinsert said resistance to obtain the desired speed regulation.

It is, therefore, the object of my invention to provide a simple and efficient device for accomplishing the foregoing.

One novel feature of my invention resides in the arrangement whereby the same resistance may be employed for starting and for speed regulation.

Another novel feature of my invention resides in the arrangement whereby the motor circuit will be automatically opened, unless a predetermined amount of resistance is removed from circuit to start the motor.

Another novel feature of my invention resides in the arrangement whereby the amount of resistance included for speed regulation may be adjusted before the motor is started and the motor circuit automatically opened unless the regulating resistance is included in circuit.

Still another novel feature resides in the arrangement whereby the motor may be started and the desired amount of regulating resistance inserted in circuit by the movement of a single controlling element to a predetermined point regardless of the amount of regulating resistance to be inserted in circuit.

Various other novel features and advantages of my invention will hereinafter be clearly and fully set forth.

For the purpose of more fully disclosing

the characteristic features of my invention, I shall describe the controller diagrammatically illustrated in the accompanying drawing.

The controller shown merely serves to illustrate the general features of my invention and does not limit my invention to any particular construction. Of course, my invention is susceptible of various modifications.

The controller illustrated includes a starting arm 1 and a speed regulating element 2, both of which are illustrated as pivotally supported upon a suitable insulating base 3. The starting arm 1 is provided with a contact brush 5 adapted to engage and move over a series of contacts 6 and contacts 7, 8 and 9. The brush 5 is adapted to engage each contact before leaving the next preceding contact. The arm 1 is provided with a suitable spring 10, tending to move the same against a stop 11 provided on the base 3, and is adapted to be held in final position by a retaining magnet 12. Of course, in lieu of the retaining magnet, I might provide any other form of locking device. The element 2 is movable between fixed stops 13 and 14 and is adapted to sweep over a series of contact buttons 15. Contact buttons 15 and the contacts 6 are electrically connected to a common resistance 17. Instead of showing the contacts 15 directly connected to the resistance 17, I have shown the same as electrically connected to the contacts 6, which, of course, produces the same result. The contact 7 is connected to the last section of resistance 17, and, when engaged by the arm 1, is adapted to cause the energization of a blow coil 18, the function of which will be hereinafter set forth. The controller, as illustrated, is provided for controlling a motor having an armature A and a shunt field winding F. Of course, my invention is applicable to other forms of motors than that illustrated.

I shall now describe the operation of the controller illustrated, at the same time setting forth, the circuit connections therefor. Assuming that the starting arm 1 is in the position illustrated, no current will flow through the motor. To start the motor, it is necessary to move the arm 1 so that the brush 5 thereof will engage the first of the series of contacts 6. This completes the motor circuit from main line 20 by conductor 21, through

the arm 1 and brush 5 to the first of the series of contacts 6, thence by conductor 22, through the shunt field winding F, by conductor 24 to main line 19. Circuit is also closed from the first of the series of contacts 6, through all of the starting resistance 17, by conductors 25 and 26, through the motor armature A, to main line 19. Thus current is supplied to both the motor armature and the shunt field winding. If the motor starts upon this operation of the arm 1, of course, the same will start with all of the resistance 17 in its armature circuit. By moving the arm 1 over successive contacts of the series of contacts 6, the resistance 17 is gradually removed from circuit, thereby gradually increasing the potential impressed upon the motor armature. When the arm 1 has been moved sufficiently to cause the brush 5, carried thereby, to engage contact button 7, all of the resistance 17 will be removed from circuit, and full line potential impressed upon the motor armature. This arrangement insures a sufficient potential to start the motor under all conditions. Upon leaving contact button 7, the brush 5 of the starting arm engages contact buttons 8 and 9. The starting arm is then held in this position by the retaining magnet 12, the circuit for which will be hereinafter traced. When the arm 1 engages contact buttons 8 and 9, the circuits of the motor armature and field winding may be traced as follows. The field circuit may be traced from contact button 9 by conductor 27, through the retaining magnet 12, to conductor 22 and thence through the field winding as already traced. The armature circuit may be traced from contact button 8, by conductor 28 through the speed regulating element 2 and through a portion of the resistance 17 to the motor armature as already traced. It will thus be seen that upon the arm 1 reaching final position, a portion of the resistance 17 is reinserted in circuit with the motor armature, thereby reducing the potential impressed thereon. The amount of resistance thus reinserted in the motor circuit depends upon the position of the element 2. As illustrated, the element 2 is so disposed that upon the starting arm 1 reaching final position, approximately one half of the resistance 17 will be reinserted in the motor circuit. Consequently, the motor will operate at a comparatively slow speed. To increase or decrease the speed of the motor, it is only necessary to move the element 2 in one direction or the other in accordance with the result which it is desired to obtain. Of course, the element 2 may be adjusted before the motor is started so that when the starting arm is moved to final position the speed of the motor will be limited to a predetermined value without any further operation of the controller. Also the element 2 may be

actuated while the motor is in operation to vary the speed thereof.

If upon the starting arm reaching final position, a considerable amount of resistance is reinserted in the motor circuit as above set forth, it is very likely that an arc would be produced as the starting arm leaves contact button 7. It is for the purpose of extinguishing such arcs that I have provided the blow-out magnet 18, which, it is apparent, becomes energized when the starting arm engages contact button 7, and will, consequently, extinguish any arc produced upon said arm leaving said contact button.

Upon deenergization of the retaining magnet from any cause whatever, the starting arm would be returned to initial position by the spring 10, thereby reinserting all of the resistance 17 in circuit and finally opening the motor circuit. Consequently, there is no danger of a careless attendant starting the motor without a proper amount of resistance in the motor circuit. Furthermore, the starting arm must be moved to final position in order to maintain the motor circuit closed, and this, of course, always insures the starting of the motor and prevents an attendant from leaving the motor circuit closed without starting the motor.

While I have shown a manually operated starting arm, it should be understood that the same might be automatically operated if desired.

I claim—

1. In a controller for electric motors, in combination, a resistance controlling element movable to one position to start the motor and to another position to restrict the speed of the motor and means for limiting the speed restrictive effect of said element when moved to said last-mentioned position.
2. In a controller for electric motors, in combination, a resistance controlling element movable to one position to start the motor and to another position to restrict the speed of the motor and means independent of said element for varying the speed restrictive effect thereof when moved to said last-mentioned position.
3. In a controller for electric motors, in combination, a resistance controlling element movable in the same direction to start the motor and then restrict the speed thereof and means necessitating movement of said element to a speed restrictive position in order to maintain the motor in operation after its release.
4. In a controller for electric motors, in combination, a resistance controlling element movable in the same direction to start the motor and then restrict the speed thereof and means for varying the speed restrictive effect of said element while in a predetermined position.
5. In a controller for electric motors, in

combination, a resistance controlling member biased in a direction to disconnect the motor from circuit, said member being movable to start the motor and then restrict the speed thereof and an electromagnet for holding said member in its speed restrictive position.

6. In a controller for electric motors, in combination, a resistance controlling member biased in a direction to stop the motor, said member being movable to start the motor and then restrict the speed thereof, an electromagnet for retaining said member in its speed restrictive position and means for varying the restrictive effect of said member while held by said magnet.

7. In combination, a resistance controlling element normally disconnected from circuit and adapted when connected in circuit to restrict the potential impressed upon the motor to restrict the speed of the motor, and a second resistance controlling element movable to a position to start the motor and then to another position to connect said first mentioned element in circuit.

8. In combination, a resistance controlling element normally disconnected from circuit and adapted when connected in circuit to restrict the potential impressed upon the motor to restrict the speed of the motor, and a second resistance controlling element movable to a position to start the motor and then to another position to connect said first mentioned element in circuit said second mentioned element automatically operating to stop the motor if released before it is moved to said second mentioned position.

9. In a motor controller, in combination, two resistance controlling elements, one for gradually increasing the potential upon the motor for starting and the other for restricting the potential impressed upon the motor for speed regulation, said second mentioned element being normally ineffective and said first mentioned element being adapted after starting the motor to render said first mentioned element effective.

10. In a motor controller, in combination, two resistance controlling elements, one for gradually increasing the potential upon the motor for starting and the other for restricting the potential impressed upon the motor for speed regulation, said second mentioned element being normally ineffective and said first mentioned element being adapted after starting the motor to render said second mentioned element effective, said first mentioned element tending to stop the motor if released before said second mentioned element is rendered effective.

11. In a controller for electric motors, in combination, a variable resistance included in the motor circuit, a controlling element adapted to remove said resistance from the

motor circuit for starting, and to include said resistance in circuit for speed regulation, and means for limiting the amount of said resistance included in circuit by said element for speed regulation.

12. In a controller for electric motors, in combination, a variable resistance included in the motor circuit, a controlling element for removing said resistance from the motor circuit for starting, and a controlling element adapted to be adjusted to include different predetermined amounts of said resistance in the motor circuit for speed regulation, said second mentioned element being normally disconnected from circuit and arranged to be connected in circuit by said first mentioned element when in a predetermined position.

13. In a controller for electric motors, in combination, a variable resistance included in the motor circuit, a controlling element for removing said resistance from the motor circuit for starting, a controlling element adapted to be adjusted to include different predetermined amounts of said resistance in the motor circuit for speed regulation, said second mentioned element being normally disconnected from circuit and arranged to be connected in circuit by said first mentioned element when in final position, means for maintaining said first mentioned element in final position, and means tending to return the same to initial position.

14. In a controller for electric motors, in combination, a resistance included in the motor circuit, controlling means therefor, adapted to permanently include different predetermined amounts of said resistance in the motor circuit for speed regulation, and means necessitating the removal of a predetermined amount of said resistance prior to the insertion of the portion, or portions, thereof for speed regulation.

15. In a controller for electric motors, in combination, two series of contacts, a common variable resistance connected to both of said series of contacts and adapted to be connected in the motor circuit, a starting element movable over one of said sets of contacts, a speed regulating element movable over the other of said sets of contacts, said starting element being adapted to be moved to remove said resistance from the motor circuit, said speed regulating element being normally disconnected from said circuit, and a contact arranged to be engaged by said starting element to connect said speed regulating element in circuit, said speed regulating element being arranged to include different predetermined amounts of said resistance in the motor circuit.

16. In a controller for electric motors, in combination, two sets of contacts, a common variable resistance connected thereto and arranged to be connected in the motor circuit.

a starting element movable over one set of contacts to remove said resistance from circuit, and an element movable over the other set of contacts to include different predetermined amounts of said resistance in the motor circuit for speed regulation, said last mentioned element being normally disconnected from circuit and adapted to be connected in circuit by said starting element after the same has been operated to remove all or a predetermined amount of said resistance.

17. In a controller for electric motors, in combination, two sets of contacts, a common variable resistance connected thereto, and arranged to be connected in the motor circuit, a starting element movable over one set of contacts to remove said resistance from circuit, an element movable over the other set of contacts to include different predetermined amounts of said resistance in the motor circuit for speed regulation, said last mentioned element being normally disconnected from circuit and adapted to be connected in circuit by said starting element after the same has been moved to a pre-determined position, means tending to return said starting element to initial position and a retaining magnet for holding said starting element in position to maintain said regulating element in circuit.

18. In a controller for electric motors, in combination, a resistance adapted to be connected in the motor circuit, a set of contacts connected therewith, an element movable over said contacts to gradually remove said resistance from circuit and adapted to be disengaged from said contacts to reinsert resistance in the motor circuit for speed regulation, and a blow out coil for disrupting the arc formed upon said element leaving said contacts.

19. In a controller for electric motors, in combination, a resistance adapted to be connected in the motor circuit, a set of contacts connected therewith, an element movable over said contacts to gradually remove said resistance from circuit and adapted to be disengaged from said contacts to reinsert resistance in the motor circuit for speed regulation, and a blow out coil for disrupting the arc formed upon said element leaving said contacts, said blow out coil being energized when said element engages the last of said contacts.

In witness whereof, I have hereunto subscribed my name in the presence of two witnesses.

FLOYD T. TAYLOR.
